COMBINING TELEPHONES AND PHONOGRAFS

Harry R. Van Deventer, New York, N. Y.

Application November 9, 1943, Serial No. 509,544

34 Claims. (Cl. 179—6)

This invention relates to combining telephones and phonographs, and has for an object the provision of means whereby a subscriber's telephone may be combined with a phonograph that will operate, in the subscriber's absence, to answer the telephone.

Another object is the provision of means whereby a subscriber's telephone, of the usual handset variety, can be combined with the phonograph without changing the interior wiring or connections of the telephone, by making two holes through the base plate thereof, to permit the introduction into the interior of the telephone casing of operating rods extending from the telephone mechanism to the phonograph mechanism, the latter being in the phonograph cabinet on which the telephone is supported.

Further objects are the provision of a simple, compact, device to answer the telephone; the provision of an improved mounting for a phonograph reproducer particularly adapted to the special use herein disclosed (but suitable for use in many other applications and arrangements where phonographs are used).

Other objects will be apparent from a perusal of the following specification, where by way of illustration, a preferred embodiment of the device is disclosed.

There are a large number of telephone instruments of the cradle, or handset, type in use all over the world and it is desirable, and is one of the objects of this invention, to provide a phonograph instrument especially adapted for use with such telephones without changing the telephone instrument or circuits, except to make two holes in the base plate of the telephone, as hereinafter described.

By the invention herein disclosed, the transmitter of the telephone is used to transmit the phonograph recording to the calling subscriber. Also, the telephone ringer is used to control the phonograph, and the telephone hook switch is used to connect the transmitter to the telephone line while the phonograph is in operation. Thus the cost of the parts necessary to accomplish these functions, when the telephone instrument is not used as herein described, is saved, and the amount of apparatus considerably reduced as compared with telephone-phonograph combinations heretofore known.

In the accompanying drawings:

Figure 1 is a side elevational view of a well known type of handset telephone supported on a phonograph, and connected for operation therewith as hereinafter described;

Figure 2 is a plan view of the top of the apparatus shown in Figure 1;

Figure 3 is a view partly in section, of the apparatus shown in Figure 1;

5 Figure 4 is a plan view looking down on the record table, shown in Figure 3.

Figure 5 is a wiring diagram of the apparatus, Figure 1.

Figure 6 is an alternate wiring diagram of apparatus in which a spring motor may be employed.

Figure 7 is a view partly in section on the line 7—7 of Figure 4.

10 Figure 8 is a view partly in section on the line 15 8—8 of Figure 3.

The numeral 10 generally denotes the phonograph cabinet, constructed in any suitable manner to contain the apparatus presently described and preferably having a drawer 11 in its lower portion for records.

15 The cabinet has a hinged top or lid 12 having a plurality of apertures 13, 13 therein to permit sound from the phonograph to pass upwardly to the telephone transmitter, as presently described.

20 The entire upper surface of the lid can be perforated, or formed of a suitable screen through which the sound will readily pass.

Secured to the lid 12, in any suitable manner, are the adjustable guide members 14, 15, 16, 17, 25 which have slotted ears as indicated at 18 engaged by thumb screws 19 so that the guides can be easily adjusted to accurately position the base 20 of the telephone casing.

30 Telephones of the type shown and described usually have a connecting cord 21 and a receiver cord 22 extending respectively from the rear and one side of the base. Therefor, the members 16 and 17 are slotted to receive these cords and this insures that the telephone will always be replaced properly on the phonograph cabinet, as it will not fit in the guide members except in the position shown on account of the cords.

35 Should it be necessary, for any reason, not to rely upon positioning the telephone by using the cords and slots as just described, a projecting tongue 23 may be attached to one edge of the base 20 and is received in a corresponding groove in one of the members, such as 17 as shown in Figures 1 and 2, thus positioning the 40 base of the telephone in relation to the phonograph cabinet.

45 The guide members 14 to 17, inclusive, may be high enough to prevent the telephone base 20 from contacting the operating levers of the phonograph cabinet.

nograph unless the base is introduced into the guides in the proper position.

The telephone casing contains the usual telephone ringer 85, condenser C, induction coil 1 and other parts, including a switching spring assembly H commonly termed the "hook switch" having a plunger, or plungers, P, extending upwardly into the cradle or pedestal portion 24 of the casing, said plunger being normally held down by the weight of the hand-set 25 comprising the usual transmitter and receiver marked T and R, respectively, in the drawings. As the details of construction of such telephones vary, no attempt is here made to describe them in detail, as any telephone of this general type may be used if it has a switching mechanism and a ringer that can be reached by the operating rods or members to be presently described.

Practically all such telephones have a switch that can be reached through a hole in the bottom plate of the casing, and the mechanism is of such a nature that, by pushing upwardly against it, the contacts can be closed and the instrument placed in circuit without displacing the handset 25 from the cradle 24. Advantage is taken of this; the handset may be slightly raised in the cradle but because of the ears retaining it on the pedestal, it will not fall off, although the telephone is connected to its line circuit.

The base plate 26 of the telephone is apertured, as shown at 27 and 28, so that when the telephone is in position on the cabinet 10, the operating rods 29, 30 will enter the casing and respectively contact the switching mechanism and the ringer therein. The apertures or holes 27, 28 are easily made in the base plates of existing telephones which can then be used with the phonograph apparatus herein described without further change.

Referring to Figure 3, 31 denotes a mounting plate that may be secured in the phonograph cabinet 10 in any suitable manner. Secured to said plate, or integral therewith, is the stem or support 32 which forms a supporting bearing for the revolvable bushing 33 to which the record table 34 is connected in any suitable manner. The record table supports a suitable phonograph record 35 which may have a plurality of spaced-apart recordings thereon, as at 36 and 37.

Secured to support 32 is the collar 38 having an irregular upper portion shown at 39 adapted to engage and position the removable support 40 which slidably fits on the support 32 and is clamped thereto by the screw 41.

The support 40 has a radially extending arm 42 upon the outer end of which is mounted the arm 43 free to move horizontally and vertically. On the outer end of arm 43 is mounted the reproducer 44 of the phonograph and this may have a horn 45 adapted to direct sound upwardly where it will find egress through the openings 13 in the top 12 of the cabinet and impinge upon the transmitter T of the handset which is positioned so as to overlie the horn as much as possible.

The reproducer has a pair of upwardly extending arms 46, 47 which support a roller 48 engaging a lifting member 49 pivoted at 50 to an arm 51 extending from the support 40. The upper edge of the member 49 has a plurality of sloping surfaces 52, 53 which incline toward the right, Figure 3, so that when said member is in the upper position shown in Figure 3, the reproducer 44 will, by reason of the sloping surface 52 or 53 and the roller 48, return by gravity to the

extreme right, the needle 54 of the reproducer being out of contact with record 35.

The lifting member or arm 49 has an inwardly extending portion 55 which extends through a slot 56 in the upper end of support 32 so as to underlie the head 57 of rod 58 which is vertically movable in support 32 as shown. An adjusting screw 59 is provided for adjusting the upper movement of the end 55 of the lifting member.

10 It will be seen that the support 40, the arms 42 and 43, reproducer 44 and horn 45, the reproducer lifting mechanism—arms 46, 47, roller 48, member 49 and its adjusting means 59 form a unitary removable unit that can be taken off the center support 32 and removed from the phonograph for examination and repair without disassembling any of these associated parts by loosening screw 41 and pulling the member 40 upwardly.

When so removed, the record 35 is easily changed or the upper surface of it cleaned. If desired, a recorder can be substituted for the reproducer 44 and a recording made upon a pre-grooved record in situ, thereby insuring accurate recordings exactly within the spaces 36, 37 on the record, as many of such spaces and corresponding slopes, such as 52 and 53 on the member 49, being used as desired.

15 The upper end of rod 58 above the head 57 thereof forms an extension tip and is reduced in diameter, as shown at 60, to fit within the sliding sleeve 61 forming the bottom of rod 29, a spring 62 being interposed between these members as shown in Figure 3. The sleeve is slotted as shown at 63 and a pin 64 permits the sleeve to telescope on 60, as indicated in Figure 6. The sleeve 61 is threaded to the rod 29, as indicated at 65, and provided with a lock-nut 66 so that the length of the tip can be adjusted.

20 30 A motor 67, mounted on plate 31, has a shaft 68 extending to a suitable speed reducer 69 which has a shaft 70 extending therefrom and operating at the proper speed, and provided at its outer end with a worm 71 engaging the worm gear 72 on vertical shaft 73 which drives the usual rubber-tired friction wheel 74 to rotate the record table 34. Any suitable drive can be used; the speed reducer can be combined with the motor in any known manner, and the entire showing 35 here is purely diagrammatic, as many suitable arrangements are well known and in common use.

25 45 The speed reducer has a second shaft 75 which is driven by motor 67 at such speed that it makes one revolution while the table 34 is making the necessary revolutions to cause the reproducer needle 54 to traverse the space 36 on the record 35. Shaft 75 has secured thereto the cams 76, 77.

50 55 Cam 76 operates the rod 58, moving same upwards (from a position of rest as shown in Figure 60 3) and holding same in the "up" position while the phonograph is in operation.

50 60 Cam 77 operates just before cam 76 completes its cycle of revolution, and cam 77 in passing, momentarily opens contacts 78 controlling the motor circuit.

65 70 The shaft 75 and cams 76 and 77 may be relatively adjustable by any suitable means so as to accurately time the points at which the rod 58 is lowered and the contacts 78 opened.

In the lid 12 is mounted a casing 79, shown in dotted lines in Figure 5, containing a relay 80 having a normally open contact 81 and an armature 82 pivoted on the casing at 83 and normally held in open circuit position by the light retractile

spring 84. Secured to the armature is the upwardly extending operating rod 30 which may be forked or otherwise formed at its upper end to engage a movable part of the telephone ringer 85—preferably the striker rod 86, so that when the ringer is operated, the armature 82 will make contact at 81 and complete a circuit from the current supply 87 via 84, 82, 81, 80 and through normally closed contacts 78 to the other side 88 of the supply circuit. This energizes relay 80 which locks in circuit with contact 81 closed, thereby completing a circuit from 87 to 84, 82, 81 motor 67 to 88 thereby energizing the motor, which operates until the contacts 78 are momentarily opened by cam 77 which opens the circuit through relay 80 releasing armature 82 and restoring the relay to open-circuit condition, stopping the motor.

Usually, telephone ringers have a biassing spring attached to the ringer armature or striker rod 86, pulling same to one side, and therefore, the spring 84 can be omitted, or can be used instead of the usual biassing spring.

Assuming that the record 35 has a recording, or recordings, thereon and that the telephone instrument is placed in position on the cabinet 10, the main switch 89 is closed to connect the device to a suitable source of current via conductors 87, 88. The apparatus is in the position shown in Figure 3—and the handset 25 is resting on plunger P and the contacts of switch H are open.

When the operator rings on line L—L, the ringer operates in the usual manner and via rod 30 closes contact 81 operating relay 80 as previously described and starting motor 67 which revolves the table 34 and the record 35 carried thereon. At the same time cam 76 raises rod 58, spring 62 is compressed and member 29 is forced upwardly against the telephone switch mechanism H, operating same without, however, completely forcing the handset 25 out of its supporting cradle 24. This places the transmitter T in circuit with the line L, L ready to transmit.

As the rod 58 moves upwardly, the head 57 thereof releases the end 55 of arm 49 upon which the reproducer 44 is suspended and the needle 54 thereof contacts the record and the sound recorded thereon emerges from horn 45, and passing upwardly through the grille or openings 13 in the top of the cabinet 12, impinges upon the transmitter T and is heard by the waiting subscriber at the calling end of line L, L.

The reproducer travels over the record space 36 to the left, Figure 3, during which travel the roller 48 also moves with it, so that when the reproducer reaches the end of the recording, the roller will be above the high point 90 of the sloping surface 52. At this time, cam 77 passes the contacts 78 which are opened, thereby opening the motor circuit; as the motor stops, cam 76 lowers rod 58, the head 57 of which engages the end 55 of arm 49 raising the latter to the "at rest" position shown in Figure 3. The arm 49 picks up roller 48 carrying reproducer 44 which is lifted away from the record, and as the roller 48 moves down the sloping surface 52, the reproducer 44 is returned to its starting or "at rest" position, shown in Figure 3.

If the reproducer is moved to the second recording space 37, the action is the same as just described, the roller 48 then coming to rest at the point 91 which will bring the needle 54 at rest above the beginning of the recording 37.

The arms 42, 43 are so connected that the reproducer 44 is free to move horizontally and ver-

tically sufficiently to function as described, and while an acoustic mechanical reproducer is shown, it will be understood that any form of electrical reproducer with the necessary amplification can be used, the power feed to the electronic circuit being taken off the control circuit, as shown at 92, Figure 5.

As such electronic reproducing circuits are well known, they are not herein described. A typical common battery telephone circuit has been shown by way of illustration, but any circuit can be used—either magneto or common battery.

The interposition of spring 62 and the adjustability of the member 61 at 65 provide an easy way of adjusting the tip of rod 29 and, as rod 58 is lowered by cam 76, the rod 28 releases the telephone hook switch H, the weight of the handset 25 engages plunger P and the telephone circuits are restored to normal open circuit position.

Obviously, the telephone can be used for outgoing calls in the usual manner without operating the phonograph, and can receive incoming calls without phonograph operation by opening switch 89 or by removing the telephone instrument from its cooperative position on the phonograph cabinet 10.

Where necessary or desirable, a spring-wind motor 93, Figure 6, may be substituted for the electric motor 67 shown in the other figures, 30 and, as this substitution will usually occur where no current supply is available, the relay 94 is connected across the telephone line L, L in series with the contacts 78 as shown. A stop-pawl 95 is connected to the gear train of the motor 93 and 35 is engaged and held by the movable member 96 of relay 94. When said relay operates, the pawl is released and the spring motor operates its shaft 68, cam 77, et cetera, same as the electric motor 67 previously described.

40 If a magneto telephone employing local batteries is employed, the wires 97, 98 connect to said batteries or to a pair of dry cells instead of to the common battery telephone line L, L, thus making any outside source of current unnecessary.

45 A winding key 99 is provided so that the motor spring can be wound when necessary. As the construction and operation of such spring motors is well known, the motor 93 is not described in detail. The apparatus within the dotted line 50 100, Figure 6, is the telephone apparatus shown in the other figures.

55 It will be seen that the interconnection between the phonograph and telephone instrument is purely mechanical and, therefore, the telephone is movable independently of the phonograph, and usable independently thereof.

Also, when the telephone instrument is removed from the top of cabinet 10, the phonograph is automatically disabled, that is to say, is rendered non-operative, until the telephone is replaced thereon, whereupon the rods 29 and 30 are automatically positioned adjacent the cooperating parts in the telephone instrument, without having to make any mechanical adjustments or disturbing the electrical wiring in the instrument.

A preferred embodiment of the invention has been disclosed herein, but it will be obvious that many changes and modifications can be made, and such changes are deemed to be within the scope of the appended claims.

What is claimed is:

1. In combination with a line circuit and a telephone instrument connected thereto includ-

ing switching mechanism a transmitter and a signalling device, a telephone answering device including an actuating member extending into said telephone instrument and operatively engaging the switching mechanism therein to connect the transmitter thereof to said circuit, a motor for operating said actuating member, a phonograph record adapted to be moved by said motor, a reproducer adjacent said record, means operated by said actuating member to cause said reproducer to first engage said record for a predetermined period and thereby cause sound to impinge upon the transmitter of said telephone and thereafter disengage said record, and means operated by said signalling device for controlling the operation of said motor.

2. In combination with a line circuit and telephone instrument connected thereto including switching mechanism a transmitter and a signalling device, a telephone answering device including an actuating member extending into said telephone instrument and operatively engaging the switching mechanism therein to connect the transmitter thereof to said circuit, a motor for operating said actuating member, a phonograph record adapted to be moved by said motor, a reproducer adjacent said record, means operated by said actuating member to cause said reproducer to first engage said record for a predetermined period and thereby cause sound to impinge upon the transmitter of said telephone and thereafter disengage said record, and means controlled by the operation of said motor for determining the running time thereof.

3. The combination as claimed in claim 2 wherein said reproducer is adjustably supported upon a movable member positioned above said record and said movable member is moved by said actuating member to move the reproducer relative to the record.

4. The combination as claimed in claim 2 wherein said last means includes contacts arranged to open the circuit supplying current to said motor.

5. In combination with a line circuit and telephone apparatus connected thereto including switching mechanism and a transmitter, a telephone answering device including an actuating member extending into said telephone instrument and operatively engaging the switching mechanism therein to connect the transmitter thereof to said circuit, a rotatable record table through which said actuating member extends, a reproducer above said table, and means controlled by the movement of said actuating member for moving said reproducer toward and away from said table.

6. In combination with a line circuit and telephone apparatus connected thereto including switching mechanism, a transmitter and a signalling device, a telephone answering device including an actuating member extending into said telephone instrument and operatively engaging the switching mechanism therein to connect the transmitter thereof to said circuit, a rotatable record table through which said actuating member extends, a reproducer above said table, means controlled by the movement of said actuating member for moving said reproducer toward and away from said table, and control means for said motor operatively connected to said signalling device.

7. In combination, a motor, an apertured record table driven thereby, a support extending through said aperture, an actuating member ex-

tending through said aperture, a reproducer above said table and movably secured to and supported by said support, and means connecting said reproducer and said actuating member whereby said reproducer may be raised and lowered above said record table by moving said actuating member.

8. The combination as claimed in claim 7 wherein said reproducer is supported on an arm above said table fulcrummed to said support, said arm having one end in engagement with said actuating member.

9. In combination, a motor, an apertured record table driven thereby, a support extending through said aperture, a collar removably secured to said support above said table, a second support, an arm pivoted to said second support and extending outwardly therefrom, a reproducer carried on said last arm and supported thereby and adapted in one position to approach the upper surface of said table, and an actuating member extending through the aperture in said record table and engaging the inner end of said arm to reciprocate the same.

10. In combination, a revolvable record table having a fixed support perpendicular to the surface thereof and extending through a central aperture therein, a movable actuating member substantially parallel to said support and extending through said aperture in said table, and a reproducer assembly removably secured to said support above said table and supported thereby including a reproducer and a supporting arm therefor adapted to be moved by said actuating member whereby said reproducer may be moved toward or away from the surface of said record table.

11. In combination, a revolvable record table having a fixed support perpendicular to the surface thereof and extending through a central aperture therein, a movable actuating member substantially parallel to said support and extending through said aperture in said table, a reproducer mounted above said table and movably supported on said support and adapted to be lowered toward said table by movement of said member and a mounting plate below said table upon which all of the foregoing parts are supported.

12. In combination, a revolvable record table having a fixed support perpendicular to the surface thereof and extending through a central aperture therein, a movable actuating member substantially parallel to said support and extending through said aperture in said table, a reproducer mounted above said table and movably supported on said support and adapted to be lowered toward said table by movement of said member, a motor, means connected to said motor and engaging said actuating member to reciprocate the same as said motor revolves, and means connected to said motor for revolving said table.

13. In combination, a revolvable record table having a fixed support perpendicular to the surface thereof and extending through a central aperture therein, a movable actuating member substantially parallel to said support and extending through said aperture in said table, a reproducer mounted above said table and movably supported on said support and adapted to be lowered toward said table by movement of said member, a motor, means connected to said motor and engaging said actuating member to reciprocate the same, and means operated by a predetermined number of revolutions of said motor for controlling the same.

14. In combination with a telephone instrument

having a transmitter and signalling mechanism, a cabinet adapted to support said instrument and having an opening subjacent said transmitter to permit sound originating in said cabinet to find egress therefrom to impinge upon said transmitter, means within said cabinet for reproducing speech including a motor-operated device and means actuated by said signalling mechanism for controlling the operation of said device.

15. In a phonograph mechanism having a movable actuating member adapted to engage and operate a telephone switching mechanism, means for adjusting the effective length of said member including an extension tip mounted for longitudinal adjustment at the extremity of said member.

16. In a phonograph mechanism having a movable actuating member adapted to engage and operate a telephone switching mechanism, an extension tip for said member, and a yielding connection between said tip and member whereby said tip and member may telescope.

17. In a phonograph mechanism having a movable actuating member adapted to engage and operate a telephone switching mechanism, means for adjusting the effective length of said member including an extension tip mounted for longitudinal movement along said member, and a spring between said tip and member tending to urge said tip outwardly while permitting same to telescope thereon.

18. In combination, a motor driven phonograph, an actuating member, means driven by said motor for moving said member, telephone switching mechanism engaged and operated to closed circuit position by the aforesaid movement of said member, and a telephone hand set adapted by gravity to move said switching mechanism to open circuit position and move said member the while.

19. In combination, a motor driven phonograph, a telephone switching mechanism, an actuating member operatively connected to said motor and engaging said switching mechanism to move same from open to closed circuit position and having an initial starting position, and a telephone handset adapted to engage said switching mechanism and by gravity restore same to open circuit position and move said member to its initial starting position.

20. The combination as claimed in claim 19 wherein a spring is interposed between the telephone switching mechanism and the actuating member to permit a yielding contact between the same.

21. In combination with a telephone instrument of the character described, a motor-driven phonograph, an actuating member extending from said phonograph and into said instrument and contacting the switching mechanism therein to move same from open to closed circuit position when said member is actuated by said motor, said member having an initial starting position, and means associated with said motor to prevent the restoration of said member to its initial starting position until said means has been moved to a predetermined position.

22. In combination, a telephone instrument having a casing, switching mechanism and signalling means mounted in said casing, a motor-driven phonograph, an actuating member extending from said phonograph to said instrument and contacting the switching mechanism therein to move same from open to closed position when said member is actuated and a second actuating member extending between said phonograph and

instrument and adapted to be moved by said signalling means, said motor being controlled by the movement of said second actuating member.

23. In combination with a telephone instrument having a casing enclosing switching mechanism and signalling means and having a base plate with apertures therein subjacent movable parts of said switching mechanism and signalling means, a motor-driven phonograph, an actuating member extending from said phonograph and through one of said apertures in said base plate and contacting said switching mechanism in said casing to move same from open to closed position when said member is actuated, and a second actuating member extending from said phonograph and through another of said apertures in said base plate and adapted to be moved by said signalling means, said motor being controlled by the movement of said second actuating member.

24. In combination, a telephone instrument having a casing, switching mechanism and signalling means mounted in said casing, a cabinet adapted to support said casing, phonograph mechanism in said cabinet, an actuating member extending through a wall of said cabinet and into said casing and contacting said switching mechanism therein to operate the same, means within said cabinet to actuate said member, and control means for said phonograph mounted within said cabinet including a member extending through a wall thereof and adapted to engage said signalling means and thereby control said phonograph.

25. In combination with a talking circuit, a telephone instrument having a transmitter and a casing, switching mechanism and signalling means mounted in said casing, a cabinet having a perforated wall adapted to support said casing, phonograph mechanism in said cabinet, means extending through a wall of said cabinet and into said casing and contacting said switching mechanism therein to operate the same, means within said cabinet to actuate said member, and control means within said cabinet including a member extending through a wall thereof and adapted to engage said signalling means and whereby upon the actuation thereof said phonograph will operate to produce sound which, passing through said perforated wall of the cabinet, may impinge upon said transmitter while said switching mechanism is operated to connect said transmitter to said talking circuit.

26. In combination, a telephone instrument including a handset having a transmitter and receiver forming a unitary structure separate from other parts of the instrument and adapted by gravity to operate the switching mechanism thereof when placed upon its normal support, said telephone also having a casing and switching mechanism therein having a plunger with which said handset is in contact when said handset is mounted upon and normally supported by said casing when not in use by the user, a phonograph, a motor for operating said phonograph, and means operated by said motor and operatively associated with said switching means to cyclically operate the same and to move said plunger and said handset to permit such operation without completely displacing said handset from its normal support whereby said phonograph may transmit sound to said transmitter while said handset is so moved.

27. In combination, a telephone instrument including a handset having a transmitter and re-

ceiver forming a unitary structure separate from other parts of the instrument and adapted by gravity to operate the switching mechanism thereof when placed upon its normal support, said telephone also having a casing and switching mechanism therein having a plunger with which said handset is in contact when said handset is mounted upon and normally supported by said casing when not in use by the user, a phonograph, a motor for operating said phonograph, and means operated by said motor and operatively associated with said switching means to cyclically operate the same whereby while said handset remains operatively associated with said switching mechanism said handset is lifted by said plunger without complete displacement of the handset from its normal support, thereby permitting said phonograph to transmit sound to said transmitter while said handset is so displaced.

28. In combination, a telephone instrument including a handset having a transmitter and receiver forming a unitary structure separate from other parts of the instrument and adapted by gravity to operate the switching mechanism thereof when placed upon its normal support, said telephone also having a casing and switching mechanism including a plunger with which said handset is in contact when said handset is normally supported on said casing when not in use by the user, signalling mechanism in said casing, a phonograph, a motor for operating said phonograph, means operated by said motor and operatively associated with said switching mechanism to cyclically operate the same and move said handset via said plunger to permit such operation without completely displacing said handset from its normal support whereby said phonograph may transmit sound to said transmitter while said handset is so moved, control means for said motor, and a mechanical connecting member extending from said signalling means to said control means whereby same is actuated by said signalling means.

29. In combination, a telephone handset having a transmitter, switching mechanism including contacts, plunger mechanism between said handset and said switching mechanism, said handset being of sufficient weight to operate said plunger to hold said contacts in open circuit position when

said handset is at rest thereon, a phonograph, means associated with said switching mechanism to move same to closed circuit position while permitting said handset to remain at rest on said plunger, and means for operating said phonograph while said contacts are in said closed circuit position whereby sounds produced by said phonograph may impinge upon said transmitter.

30. In combination, a telephone having a ringer, a phonograph and control means therefor spaced apart from said telephone and mechanical means extending between said ringer and said control means whereby the latter is operated by the actuation of said ringer.

31. The combination as claimed in claim 30 wherein the telephone instrument has a casing in which the ringer is mounted, and the mechanical means includes a pivoted member adapted to be moved by the operation of a moving part of said ringer and extending therefrom to said control for actuating the same.

32. The combination as claimed in claim 30 wherein said mechanical means is adapted to automatically engage and disengage the ringer whereby the telephone is movable independently of the phonograph and usable independently thereof while said means and said phonograph remain connected together.

33. In a combined apparatus of the class described, a telephone line, a telephone connected to said line, a phonograph, means in said phonograph and telephone for conjointly controlling the starting of said phonograph including a mechanical member connecting same with a moving part of the telephone, and means for stopping said phonograph after a predetermined running period.

34. A communication circuit, transmitting apparatus connected thereto including switching mechanism whereby the transmitting apparatus may be connected to said circuit, a sound device including a mechanical motor, means operated by said motor for operating said switching mechanism, a control device connected to said circuit and arranged to cause said motor to operate said sound device, and means controlled by the operation of said motor for actuating said control device to stop said motor in timed relation to the operation of said first means.

HARRY R. VAN DEVENTER.
